ABSTRACT

A grinding machine having a pair of vertically aligned grinding wheels mounted upon spindles for rotation about parallel axes. Elongated guides extend toward and away from a grinding region disposed between the wheels to guide a plurality of workpieces into engagement with and away from the grinding wheels. The guides provide tunnel-like inlet and outlet guide passages communicating with the grinding region. A large quantity of cooling fluid is supplied to and confined to the grinding region. A loading rail is vertically movable from a loading position wherein a plurality of workpieces can be disposed thereon, to an unloading position wherein the loading rail is aligned with the inlet guide. A reciprocal pushing device is substantially aligned with the loading rail when in its unloading position for causing the workpieces thereon to be pushed through the inlet guide passage and into the grinding region for engagement by the grinding wheels. Suitable retarding and holding structures are associated with the outlet guide for insuring that the workpieces remain closely adjacent one another and for preventing the workpieces from moving backward into the grinding region after retraction of the pushing device.

GRINDING MACHINE

CROSS REFERENCE TO RELATED APPLICATION

This application is a continuation-in-part of my co-pending U.S. Pat. application Ser. No. 1 256, filed Jan. 7, 1970, and entitled "Grinding Machine" now U.S. Pat. No. 3,616,579.

FIELD OF THE INVENTION

This invention relates in general to a grinding machine and, more particularly, to a type thereof especially adapted to simultaneously grind two substantially opposed surfaces of a relatively hard workpiece, the grinding operation being performed accurately, automatically and quickly so that the machine can be adapted to high production operations.

BACKGROUND OF THE INVENTION

Persons familiar with the use of grinding equipment in performing an operation on relatively hard workpieces have long recognized the difficulties encountered in the grinding of two nonplanar or irregular faces of a hard workpiece, such as one made from Ferrite, while maintaining a specified dimensional relationship between such faces. Heretofore, it has been customary to grind one face of the workpiece by means of a diamond-surfaced grinding wheel and then grind the second face, often on a second machine. However, especially where the workpiece is small or has an irregular shape, it is extremely difficult to produce uniformly similar pairs of ground faces on the successive parts. Moreover, the existing, two-step process requires at least twice as long for each piece, involves considerable additional handling and usually results in numerous rejects.

For purposes of example, only, specific reference is herein made to a particular workpiece, namely, a fixed field magnet made of Ferrite for a small motor, because this workpiece has given rise to the aforementioned problem of accurately matching the shapes and dimensions of successive pairs of ground surfaces. It is important that the thickness of the field magnet is uniform in order to provide uniformly consistent and effective motors. In many cases, it is necessary to maintain tolerances of less than five thousandths of an inch and this has not been possible heretofore by means of automatic equipment capable of a large, low-cost output. That is, it has previously been necessary to produce this type of a workpiece either by a high-cost machining operation or by a relatively slow and high-cost, two-step grinding operation, both of which were performed substantially manually.

It is well known that the grinding wheel or grinding wheels must be removed from the spindles of a grinding machine, rather frequently in some instances, to repair them or to replace them with grinding wheels of different contours. Where the workpiece is relatively small, as in the case of a one-piece field magnet for a fractional horsepower motor, such removal has, in the past, been difficult. The grinding wheel spindle is usually supported in and extends from both ends of a bearing assembly, and the grinding wheel is sleeved onto one extended end of the spindle. However, parts of the grinding machine, which hold or guide the workpiece, frequently extend across the face of the grinding wheel or wheels, and these parts must be removed before the grinding wheel or wheels can be released from or

placed upon the grinding wheel spindles. That is, there is insufficient room for axial movement of the grinding wheel beyond the end of its spindle to permit removal of the grinding wheel. However, in most of these instances there is adequate room for radial movement of the grinding wheel relative to the spindle, in at least one radial direction, if the spindle did not prevent such movement.

Where two radially aligned grinding wheels are used to simultaneously perform a surfacing operation on opposite sides of a workpiece, it is not uncommon to mount the grinding wheels on spindles supported by two separate bearing assemblies which are adjustably mounted upon a supporting column. Where one of the grinding wheels is directly above the other grinding wheel, adjustment of the radial distance between the two grinding wheels is considerably more complicated than where, for example, the two grinding wheels are on the same horizontal level. The weight of the grinding wheel spindle and bearing assembly can make adjustment difficult and inaccurate. As a result, existing devices for effecting such radial adjustment between a pair of grinding wheels have been complicated and difficult to use, or inaccurate.

Accordingly, a primary object of this invention is the provision of a grinding machine capable of simultaneously and quickly performing grinding operations on two different surfaces, such as nonplanar or irregular surfaces, of the same workpiece which is fabricated from an extremely hard material, such as Ferrite, while, at the same time, producing a uniformly accurate grinding operation on successive workpieces in a relatively short period of time.

A further object of this invention is the provision of a grinding machine, as aforesaid, which performs a grinding operation automatically, which is capable of gripping and holding a plurality of workpieces firmly and accurately within a row for permitting said plurality of workpieces to be efficiently and rapidly ground during each cycle of the grinding machine, which is capable of being rapidly cycled to permit the accurate and efficient grinding of large quantities of workpieces within a relatively short time period, and which can be efficiently operated while requiring only a minimum of operator skill.

Still a further object of this invention is the provision of a grinding machine, as aforesaid, which permits large quantities of cooling fluid, such as water, to be supplied to the grinding region to permit the rapid and efficient grinding of large quantities of workpieces, while at the same time the machine structure and the manner in which it is associated with the workpieces prevents the cooling water from being discharged or thrown externally of the machine.

Another object of the present invention is to provide a grinding machine, as aforesaid, which includes elongated substantially stationary guide rail structure extending into, through and beyond a grinding region disposed between a pair of grinding wheels for permitting a plurality of workpieces disposed end-to-end within a row to be continuously moved, one after another, through the grinding region, and in which the guide rail structure includes a tunnel-like guide member disposed on the inlet and outlet sides of the grinding region for closely surrounding and confining the incoming and outgoing workpieces to prevent cooling fluid from being discharged therethrough.

Still another object of the present invention is the provision of a grinding machine, as aforesaid, which has loading structure for permitting a plurality of workpieces to be disposed within a row while a further plurality of workpieces is being ground, said first-mentioned plurality of workpieces then being automatically moved into a position in alignment with the inlet guide member after completion of the previous grinding cycle to permit the immediate initiation of a further grinding cycle.

Other objects and purposes of the invention will become apparent to persons familiar with this type of equipment upon reading the following description and examining the accompanying drawings.

BRIEF DESCRIPTION OF THE DRAWINGS

FIG. 1 is a perspective view of a grinding machine embodying the invention.

FIG. 2 is a side elevational view of the grinding machine, same being illustrated with the protective covers on the housing surrounding the grinding wheels removed and with the loading elevator in its lowered position.

FIG. 3 is a top view of the machine illustrated in FIGS. 1 and 2.

FIG. 4 is an end view of the machine as taken from the right side of FIG. 2.

FIG. 5 is a fragmentary sectional view taken along the line V—V in FIG. 6.

FIG. 6 is an enlarged fragmentary side elevational view illustrating therein only the structure directly associated with the grinding region.

FIG. 7 is a top view of the guide rail structure illustrated in FIG. 6.

FIG. 8 is a fragmentary sectional view taken along the line VIII—VIII in FIG. 6.

FIG. 9 is a fragmentary sectional view taken along the line IX—IX in FIG. 6.

FIG. 10 is a sectional view taken along the line X—X in FIG. 6.

FIG. 11 is a top view of the loading and transfer mechanisms.

FIG. 12 is a fragmentary elevational view, partially in cross-section, taken along the line XII—XII in FIG. 11.

FIG. 13 is a fragmentary elevational view taken along the line XIII—XIII of FIG. 11.

FIG. 14 is a fragmentary cross-sectional view taken along the line XIV—XIV in FIG. 13.

FIG. 15 is a diagram of the hydraulic circuit of the grinding machine.

FIGS. 16A and 16B are a diagram of the electrical control circuit of the grinding machine.

FIG. 17 is a fragmentary top plan view of an alternate grinding machine embodying the invention.

FIG. 18 is a sectional view taken along the line XVIII—XVIII in FIG. 17.

FIG. 19 is a sectional view taken along the line XIX—XIX in FIG. 18.

FIG. 20 is a sectional view taken along the line XX—XX in FIG. 18.

Certain terminology will be used in the following description for convenience in reference only, and will not be limiting. For example, the words "upper," "lower," "front" and "rear" will have reference to the machine as appearing in FIGS. 1 and 2 which illustrate the front of the machine. The words "inner" and "outer" will refer to directions toward and away from

the geometric center of the device and designated parts thereof. Said terminology will include the words above specifically mentioned, derivatives thereof and words of similar import.

5

SUMMARY OF THE INVENTION

The objects and purposes of the invention, including those set forth above, have been met by providing a grinding machine having a base structure adjustably

10 supporting a pair of vertically aligned bearing assemblies, each of which rotatably supports a grinding wheel spindle. The spindles are connected at corresponding ends of each to a pair of separate motors. The other ends of the spindles support a pair of radially aligned

15 grinding wheels. In this particular embodiment, the peripheries of said wheels are respectively concave and convex to define an arcuate grinding region therebetween adapted to receive therein arcuate workpieces. Elongated stationary guide rail structure extends tan-

20 gentially in opposite directions from the grinding region and includes a passageway corresponding to and only slightly larger than the shape of the workpieces to enable the workpieces to be slidably guided into and away from the grinding region. A reciprocating ram

25 slidably extends into the passageway in the guide rail structure for permitting a plurality of adjacent workpieces to be continuously moved, one after another, into and through the grinding region during a single advancing stroke of the ram.

30 A movable loading rail, when disposed out of alignment with the guide rail structure, is adapted to have a plurality of workpieces mounted thereon in end-to-end relationship within a longitudinally extending row. The loading rail is then movable into alignment with

35 the inlet portion of the guide rail structure after the ram has been fully retracted. The subsequent advancing movement of the ram causes the workpieces to be slidably moved into the passageway of the guide rail structure and through the grinding region, during which

40 movement the loading rail is again moved into a loading position to permit a further plurality of workpieces to be loaded thereon. The guide rail structure, on the opposite sides of the grinding region, is provided with suitable fluid passages for directing cooling fluid di-

45 rectly into the grinding region. A retarder device, which may be either weight or spring actuated, coacts with the row of workpieces discharged from the grinding region for maintaining the workpieces directly adjacent one another.

50

DETAILED DESCRIPTION

FIGS. 1-6 illustrate therein a grinding machine 10 constructed according to the present invention, which machine includes a frame 11 having a substantially planar base structure 12. A pair of substantially vertically aligned and vertically spaced grinding wheels 13 and 14 are rotatably supported on the frame and disposed above the base structure 12, whereby the grinding wheels define a small grinding region therebetween adapted to receive workpieces. A loading mechanism 16 (FIGS. 1 and 3) projects forwardly of the machine for permitting a plurality of workpieces W to be positioned thereon substantially within a longitudinally extending row, whereupon the row of workpieces is then slidably moved onto a transfer mechanism 17 (FIG. 2). The transfer mechanism 17 is, in the illustrated embodiment, constructed as an elevator mechanism

55

60

65

whereby the workpieces are then moved vertically upwardly into alignment with an inlet guide rail structure 18. A pusher mechanism 19 is disposed for engaging the row of workpieces on the transfer mechanism 17 and pushing same into and through the inlet guide rail structure 18 and into the grinding region defined between the wheels 13 and 14. The pushing mechanism then causes the workpieces to be pushed into an outlet guide rail structure 21, and further through a retarder device 22, whereupon the finished workpieces are discharged from the machine, such as onto a conventional discharge conveyor 23.

The grinding wheel 13, as illustrated in FIGS. 4 and 5, is secured to the outer end of a spindle assembly 26 rotatably supported on a bearing assembly 27, the latter being mounted on an upwardly extending pedestal 28 which comprises a portion of the frame 11. The grinding wheel 14 is similarly mounted on the outer end of a spindle assembly 29 rotatably supported by a further bearing assembly 31 which is also mounted on the pedestal 28. The rearward end of spindle assembly 26 is interconnected to a drive motor 32 by an intermediate belt drive 33, and the other spindle assembly 29 is similarly connected to a further drive motor 34 by a further intermediate belt drive 36. The motors 32 and 34 are each mounted on an upwardly extending column 37 which also comprises a portion of the frame 11. The bearing assemblies 27 and 31 are each preferably individually adjustable within a plane containing therein the axes of the spindle assemblies 26 and 29 for permitting the grinding wheels 13 and 14 to be vertically moved toward or away from each other to thus accommodate the desired workpiece thickness. The structure for permitting the vertical adjustment of the individual bearing and spindle assemblies, and the specific structure of the bearing and spindle assemblies, is disclosed in greater detail in my above-mentioned copending U.S. Pat. application Ser. No. 1 256, now U.S. Pat. No. 3,616,579, particularly in FIGS. 3 and 9 thereof.

In the illustrated embodiment, the grinding wheels 13 and 14 have coacting concave and convex peripheral grinding surfaces (see FIG. 5) which are slightly radially spaced to define an arcuate grinding region therebetween, which region is designed to permit workpieces having an arcuate or U-shaped configuration to pass therebetween. However, the grinding surfaces as formed on the wheels 13 and 14 could have any desired configuration to permit simultaneous grinding of opposite workpiece surfaces, such as arcuate or irregular surfaces. The grinding wheels 13 and 14 are disposed within and substantially totally enclosed by a boxlike shroud 38 (FIG. 2) for confining the cooling fluid utilized during the grinding operation.

The workpieces are slidably guided into the grinding region defined between the wheels 13 and 14 by means of the tunnel-like inlet guide rail structure 18 which, as illustrated in FIGS. 6-8, includes an elongated center rail 39 fixedly secured to a base pedestal 12A, as by screws 41, and having an upper convex guide surface 42 thereon. The end surface of the center guide rail 39 terminates directly adjacent the periphery of the grinding wheel 14 and has a profile corresponding to the circular and axial profile of the wheel so that the rail is thus closely adjacent to and substantially uniformly spaced from the wheel across the complete width thereof.

A pair of parallel side rails 43 and 44 are disposed on opposite sides of the center rail 39. The side rails extend upwardly above the opposite sides of the convex guide surface 42 and have oppositely inclined guide surfaces 46 and 47 formed thereon for engagement with the opposite edges of a workpiece. The center rail 39 and side rails 43 and 44 are substantially surrounded by a downwardly opening channel-shaped cover 48 which is fixedly secured to the base pedestal 12A by any conventional means, such as screws 49. The cover 48 includes opposite leg portions 51 and 52 which bear on the base pedestal 12A and are disposed directly adjacent the external sides of the side rails 43 and 44. The upper ends of the legs 51 and 52 are interconnected by a top wall 53 which has an internal concave guide surface 54 disposed upwardly from and directly opposite the convex guide surface 42. The opposed guide surfaces 42 and 54, and the opposed guide surfaces 46 and 47, thus define an inlet passageway 56 having an arcuate cross-section and extending longitudinally throughout the complete length of the inlet guide rail structure 18. The passageway 56 has a configuration which is substantially the same as, but slightly larger than, the workpieces W to provide a close confining structure for accurately guiding the workpieces into the grinding region.

The end of the top wall 53 directly adjacent the grinding wheel 13 is also provided with a profile thereon which corresponds to both the circular and axial profile formed on the periphery of the grinding wheel 13. For this purpose, the upper end wall of the guide rail structure 18 is formed with an arcuate configuration 57 generated substantially about the rotational axis of the wheel 13, with the center portion 58 of the end wall projecting outwardly to extend into the recess defined by the concave periphery of the wheel 13.

The top wall 53 also has a flow passage 59 extending therethrough and terminating in a discharge opening 61 disposed directly adjacent the periphery of the wheel 13. The other end of passage 59 terminates in an inlet opening 62 which is connected a suitable conduit (not shown) for permitting cooling fluid, such as water, to be supplied to the grinding region. A further flow passage 63, defined by an undercut recess formed in the end of center rail 39, communicates with a further conduit 64 for permitting a further stream of cooling fluid to be discharged into the grinding region directly adjacent the periphery of the lower wheel 14.

The side rails 43 and 44 extend longitudinally of the grinding machine in a direction substantially perpendicular to the plane defined by the rotational axes of the grinding wheels 13 and 14. The rails 43 and 44 are laterally spaced apart by a sufficient distance to enable same to pass on opposite axial sides of the grinding wheel 14, whereby the rails 43 and 44 thus not only comprise a portion of the inlet guide rail structure 18, but also extend through the grinding region and comprise a portion of the outlet guide rail structure 21. The guide rails 43 and 44 also extend through the retarder device 22, with the rightward ends of the rails terminating adjacent the edge of the frame pedestal 12B (FIG. 6). The side rails 43 and 44 thus support and guide the workpieces as they move through the grinding region between the wheels 13 and 14.

Considering now the tunnel-like outlet guide rail structure 21, same is substantially identical to the inlet guide rail structure 18 and includes a center guide rail

66 (FIG. 9) fixedly secured to the frame pedestal 12B and having an upper convex guide surface 67. The center rail 66 has the side rails 43 and 44 disposed on opposite sides thereof, with same in turn being substantially surrounded by a downwardly opening channel-shaped cover 68 which is substantially identical to the previously described cover 48. The cover 68 also has an internal concave guide surface spaced opposite the guide surface 67 to define therebetween an outlet passageway 71 aligned with the inlet passageway 56. Passageway 71 also has a configuration substantially the same as but slightly larger than the cross section of the workpieces.

The forward ends of the center rail 66 and cover 68 terminate directly adjacent the periphery of the wheels 14 and 13, respectively, and have a configuration corresponding to the circular and axial profiles formed on the peripheries of the wheels. The top wall of the cover 68 also has a fluid passage 72 therethrough adapted to be connected to a conduit 73 (FIG. 1) for discharging cooling fluid directly into the grinding region adjacent the periphery of the upper wheel 13. The center rail 66 also has a fluid passage 74 (FIG. 6) connected to a conduit 76 for permitting the discharge of liquid coolant directly into the grinding region adjacent the periphery of the lower wheel 14.

The outlet guide rail structure 21 also has a holding device associated therewith for preventing the workpieces, after they have passed through the grinding region, from being moved back into the grinding region by the pressure or suction created by the streams of cooling fluid. For this purpose, the outlet rail structure 21 has a holding lever 77 disposed within the forward end of the fluid passage 72 and pivotally mounted on the cover 68 by means of a transversely extending pivot pin 78. The free end of the lever 77 has a downwardly projecting tooth 79 positioned adjacent the periphery of the wheel 13. The tooth 79 extends through a small elongated slot 81 (FIG. 7) formed in the wall 82 which separates the fluid passage 72 from the guide opening 71. The tooth 79 extends downwardly into the guide opening 71, but has a cam surface 83 formed on the lower side thereof to permit it to be cammed upwardly when workpieces pass through the guide opening 71. The purpose of the holding lever 77, and the manner in which it coacts with the workpieces, will be explained in greater detail hereinafter.

The side rails 43-44 and center rail 66 also extend rearwardly beyond the cover 68 so as to be partially surrounded by the retarder device 22. The retarder device 22, as illustrated in FIGS. 6 and 9, comprises a downwardly opening channel-shaped member 84 which is hingedly supported on a pair of opposed brackets 86 by means of hinge bolts 87. The brackets 86 are fixedly secured to the frame pedestal 12B. The channel member 84 is hingedly supported adjacent its leftward end, so that the weight of the channel member 84 causes the rightward end thereof to pivot downwardly (clockwise in FIG. 6), whereby the internal concave surface 88 formed thereon bears against the upper surfaces of the workpieces W as they are slidably moved longitudinally (rightwardly in FIG. 6) of the rails. The channel member 84 thus exerts a frictional drag on the workpieces which tends to impede their rearward (rightward) movement so that the workpieces disposed forwardly of the device 22 remain in end-to-end contact with one another.

While retarder device 22 may operate solely due to its own weight, same may be entirely replaced or supplemented by a spring-urged retarder having springs 89 for urging channel member 84 into frictional engagement with the workpieces.

Alternately, the retarder device 22 may be replaced by a fluid pressure cylinder substantially aligned with the workpieces for applying a retarding force thereto, as disclosed in my above-mentioned copending application.

The rearward ends of the side rails 43 and 44 and the center rail 66 are fixedly interconnected by means of a bolt 91 (FIGS. 6 and 7) extending transversely therebetween. The bolt 91 extends through enlarged openings 92 formed in the side rails for permitting the side rails to be vertically adjusted relative to the center rail 66. For this purpose, there is additionally provided a pair of eccentric adjusting devices 93 and 94 associated with the inlet and outlet guide rail structures 18 and 21, respectively. The eccentric adjusting devices 93 and 94 are identical and thus only the device 93 will be described in detail.

The eccentric adjusting devices 93 (FIG. 8) includes an eccentric sleeve having three cylindrical portions 96, 97 and 98. The cylindrical portions 96 and 98 are coaxially aligned but are eccentric relative to the intermediate cylindrical portion 97, which portion 97 is rotatably supported in the center rail. The eccentric sleeve also has an opening 99 extending longitudinally thereof, which opening is concentric with the intermediate cylindrical portion 97. An elongated screw 101 extends through the opening 99 and has the end thereof threadably engaged within a threaded opening 102 formed in the leg 52 of the cover 48. The other end of the screw 101 has a head 103 disposed in abutting engagement with a hexagonal portion 104 which is fixedly, here integrally, connected to the exposed end of the portion 96. The screw 101, when tightened, prevents rotation of the eccentric sleeve.

To permit the rails 43 and 44 to be vertically displaced relative to the center rail 39, the eccentric cylindrical portion 96 is snugly but rotatably received in an opening 106 formed in the side rail 43, while the eccentric cylindrical portion 98 is snugly but rotatably received within a coaxially aligned opening 107 formed in the side rail 44. A further opening 108, formed in the cover leg 51, is substantially larger than the cylindrical portion 96 to permit it to freely and eccentrically rotate within the opening 108. Thus, by attaching a suitable tool, such as a wrench, to the hexagonal portion 104, the eccentric sleeve can be rotated whereby the eccentric sleeve portions 96 and 98 coact with the rails 43 and 44 to thus cause them to be vertically displaced relative to the center rail 39. Accordingly, by suitable rotation of both eccentric devices 93 and 94, the rails 43 and 44 can be moved vertically relative to the center rails 39 and 66 to permit the grinding machine to accommodate workpieces having slightly different shapes or sizes.

The workpieces W are slidably advanced along the side rails 43 and 44 by means of the pusher mechanism 19 which, as illustrated in FIGS. 2, 3, 6 and 10, includes a fluid pressure cylinder 109 having a reciprocal piston rod 111 extending therefrom. The end of the piston rod 111 is secured to a ram 110 having a slide block 112 which is slidably supported on a pair of parallel guide rods 113 and 114 disposed on opposite sides of

the piston rod 111. The guide rods 113 and 114 extend between and are stationarily mounted on a pair of fixed frame plates 116 and 117 (FIG. 2). The slide block 112 has a recess 118 (FIG. 10) formed in the rearward side thereof, and a mounting block 119 is disposed within the recess 118 and fixedly connected to the slide block 112 by screws 121. The mounting block 119 has an elongated pushing member 122 fixedly secured thereto and extending outwardly therefrom, which pushing member 122 is adapted to slidably extend into the passageways 56 and 71. The pushing member 122 has an arcuate cross-section substantially the same as but slightly smaller than the arcuate cross-section of the passageways, whereby the free end of the pushing member 122 can thus engage a workpiece W to slidably move a row of said workpieces through the passageway 56, through the grinding region between the wheels 13 and 14, and into the passageway 71. The pushing member is thus of substantial length so that the free end of the pushing member 122 extends at least part way into the passageway 71, as illustrated by dotted lines in FIG. 6, when the ram 110 is in its forward position. This thus causes the endmost workpiece to be disposed beyond the tooth 79 formed on the holding lever 77. When in this extended position, the slide block 112 is positioned directly adjacent the leftward ends of the side rails 43 and 44, substantially as illustrated in FIG. 6. On the other hand, when the ram 110 is in its fully retracted position, then the free end of pushing member 122 is spaced leftwardly a substantial distance from the ends of the side rails 43 and 44, as illustrated by the dotted line position 122A in FIG. 6, to thus permit a new row of workpieces to be moved upwardly by the transfer mechanism 17 into the space between the pushing member 122A and the inlet guide rail structure 18. This latter-mentioned positional relationship of the transfer mechanism 17 is illustrated by dotted lines in FIG. 6.

The transfer mechanism 17, as illustrated in FIGS. 11 and 12, includes a turntable 123 secured to the upper end of a support post 124. The support post is rotatably and slidably supported within an annular bearing plate 126 held in position by a sleeve 127 fixedly connected between the bearing plate 126 and a stationary mounting plate 128. The mounting plate 128 is secured to the upper end of a fluid pressure cylinder 129 which, at its lower end, is stationarily mounted on a frame plate 131. The cylinder 129 has a reciprocal piston rod 132 extending from the upper end thereof, which piston rod is axially connected to the lower end of support post 124 by a swivel member 133 for permitting support post 124 to freely rotate relative to the piston rod 132.

The base structure 12 has a plate 134 rigidly secured relative thereto, which plate mounts thereon a radially projecting roller 136. Roller 136 extends into a curved cam groove 137 formed in a cam member 138 fixedly secured to the inner surface of an annular sleeve 139 attached to and extending downwardly from the lower surface of the turntable 123. The annular sleeve 139 extends into a stationary annular shroud 141. The cam groove 137 is curved to extend both circumferentially and axially so that vertical movement of the turntable 123 between its lowermost and uppermost positions also causes a predetermined angular displacement thereof.

The vertical travel of the transfer mechanism 17 is controlled by a pair of limit switches LS-4 and LS-5 dis-

posed below the fluid pressure cylinder 129. The piston rod 132 extends from the lower end of the cylinder and has a pair of switch cams 146 and 147 threadedly mounted thereon, which cams are disposed for contact with the limit switches LS-4 and LS-5, respectively, when the turntable is in its respective upper and lower positions.

The turntable 123 is provided with a transfer rail 148 secured to the upper surface thereof and extending substantially radially thereof. The transfer rail 148 includes a center rail portion 149 having an upper convex surface and a pair of side rail portions 152 and 153 having oppositely tapered guide surfaces formed on the upper ends thereof. The transfer rail 148 thus has a cross-sectional configuration substantially the same as the center rail and side rails of the inlet guide rail structure 18. Thus, a plurality of workpieces W can be disposed in a row in end-to-end relationship on the transfer rail when same is in the lowered loading position illustrated by solid lines in FIGS. 11 and 12, with the row of workpieces then being slidably moved by the pushing member 122 from the transfer rail 148 into the inlet guide rail structure 18 when the transfer mechanism has been moved into the raised unloading position illustrated by dotted lines in FIGS. 11 and 12.

When the turntable 123 of the transfer mechanism 17 is in its lowered position, as illustrated by solid lines in FIGS. 11 and 12, the rail 148 is directly adjacent and substantially aligned with the loading mechanism 16 so that a row of workpieces on the loading mechanism 16 can be slidably moved onto the rail 148, whereby energization of the transfer mechanism causes the row of workpieces to be moved angularly and upwardly to a position in alignment with the passageway 56 formed by the inlet guide rail structure 18. In order to permit this loading operation to be performed, the loading mechanism 16 (see FIGS. 11-14) includes an elongated loading rail 157 which is substantially identical in cross-section to the transfer rail 148. The loading rail 157 is fixedly mounted on a horizontal frame element 156 and projects outwardly from the front side of the machine to thus be readily accessible to an operator standing in front of the machine. This thus permits the operator to position a plurality of small arcuate workpieces W on the loading rail 157, with the workpieces being positioned substantially adjacent one another to thus form a longitudinally extending row of workpieces.

The loading mechanism 16 also includes a pair of substantially parallel guide rods 158 disposed on opposite sides of the loading rail 157 and supported at their opposite ends by stationary brackets 159. A U-shaped slide block 161 is slidably supported on the guide rods 158 and is fixedly secured to one end of an elongated transfer slide 162, which slide has the forward end thereof spaced above and movable along the loading rail 157. The transfer slide 162, as illustrated in FIG. 14, has an arcuate cross-section similar to the cross-section of the workpieces W. The transfer slide 162 also has a handle 163 to permit the transfer slide to be manually or power actuated for movement between a retracted position as illustrated by solid lines in FIG. 13 and an advanced position as illustrated by dotted lines in FIG. 13.

CONTROL SYSTEMS

The hydraulic and electrical control systems for the

grinding machine 10 are set forth in FIGS. 15 and 16, respectively, and will be briefly described hereinbelow for purposes of completeness.

The hydraulic system, as illustrated in FIG. 15, is provided to control the energization of the fluid pressure cylinders 109 and 129 associated with the pusher mechanism 19 and transfer mechanism 17, respectively. For this purpose, the hydraulic system includes a conventional pump 166 supplied with fluid from a reservoir 167 by means of an intermediate line 168 having a strainer 169 associated therewith. The pump 166 is driven by a conventional electric motor 171, with the pressure fluid from the pump being supplied into a pair of supply lines 172 and 173. The flow of fluid through the lines 172 and 173 is respectively controlled by a pair of conventional four-way spool valves 174 and 176, each of which are operated by conventional solenoids 177. The four-way valve 174 controls the flow of fluid into and out of a pair of lines 178 and 179 which are respectively connected to the opposite ends of the pressure cylinder 129. The fluid discharged from the pressure cylinder 129 is permitted to flow into a drain line 181 which in turn communicates with the reservoir. The other four-way valve 176 similarly controls the flow of fluid from the line 173 into a pair of lines 182 and 183 which are connected to the opposite ends of the pressure cylinder 109. A further drain line 184 communicates with the valve 176 for permitting discharge of fluid to the reservoir. The line 183 communicating with the cylinder 109 also has a conventional two-way spool valve 186 associated therewith, which valve is normally maintained in the illustrated position by a spring 188. However, shifting of valve 186 by solenoid 187 results in a closing of line 183 for permitting the pressure fluid within the end of the cylinder 109 to be trapped therein.

Considering now the electrical system for the grinding machine 10, same is diagrammatically illustrated in FIGS. 16A and 16B utilizing conventional symbols and notations. In view of the completeness of the electrical circuit diagram, it is believed that those familiar with such circuitry will readily appreciate the operation of the grinding machine. However, the more essential aspects of the control circuitry, and particularly the manner in which the limit switches coact with the grinding machine for controlling the operations thereof, will be briefly described below. In conjunction with the circuitry illustrated in FIGS. 16A and 16B, reference will also be made to FIGS. 2, 11 and 12 which disclose therein the positions of the limit switches and the manner in which they coact with the ram assembly and the elevator mechanism.

Referring particularly to FIG. 2, there is mounted on the frame of the machine a plurality of limit switches, namely the limit switches LS-1, LS-2, LS-3, LS-7, LS-8 and LS-11, all positioned for contact and actuation by suitable dogs or projections fixedly secured to and movable with the ram 110. The limit switch LS-1 is engaged by the ram projection 189 when the ram is moved into its fully retracted position, whereas the limit switch LS-3 is engaged by the ram projection 189 when the ram is moved into its fully extended or forward position. The limit switches LS-1 and LS-3 thus control the travel limits of the ram. The ram also engages the limit switch LS-11 when it approaches its fully extended or forward position, which limit switch in turn controls a valve (not shown) used for control-

ling the flow of cooling fluid to the flow passages formed in the inlet and outlet guide rail structures. For this purpose, the limit switch LS-11 is positioned so that it is contacted by the ram after the forward end of the ram has passed through the grinding region, whereupon limit switch LS-11 is then contacted for controlling the valve to thus stop the further flow of cooling fluid to the grinding region until a further grinding cycle is in progress. Suitable dogs or lugs fixed to the ram are also disposed for engagement with limit switches LS-2, LS-7 and LS-8. The limit switch LS-2 is provided for controlling the start of the forward ram feeding movement, whereas limit switch LS-7 acts as an interlock and is positioned for engagement with the ram after the free end of the ram has passed slightly beyond the transfer rail, whereby actuation of limit switch LS-7 thus permits energization of the elevator mechanism 17 to permit same to be lowered for reloading. The limit switch LS-8 is engaged when the ram has been retracted beyond the elevator to thus release the interlock and permit the elevator to be raised into its upper position in alignment with the inlet guide rail structure.

The vertical movement of the elevator mechanism is controlled by the further limit switches LS-4 and LS-5 illustrated in FIG. 12. The limit switch LS-6 (FIG. 11) is positioned for contact by the turntable 123 when same has been moved upwardly and rotatably moved into a position wherein it is in alignment with the inlet guide rail structure 18.

The grinding machine is provided with still a further limit switch LS-10 which is actuated, as by being contacted by the ram, after the free end of the ram is at least partially received within the guide opening 56 for again opening the coolant flow control valve (not shown) to thus permit coolant to again be supplied to the grinding region to permit the initiation of a new grinding cycle.

A further limit switch LS-9 (FIG. 13), disposed for engagement by the slide block 161, prevents upward movement of the elevator mechanism whenever the slide block 161 is moved away from (leftwardly in FIG. 13) its retracted position.

OPERATION

The operation of the above-described grinding machine will be briefly summarized to insure a complete understanding thereof.

In the following operational description, it will be assumed that the grinding machine 10 is initially positioned with the pusher mechanism 19 in its fully retracted (leftward) position. It will also be assumed that the transfer mechanism 17 is in its uppermost position wherein the transfer rail 148 is aligned with the inlet guide rail structure 18 (as shown by dotted lines in FIGS. 6 and 11). In this position, and assuming that a row of workpieces W is disposed on the transfer rail 148, then the fluid pressure cylinder 109 will be energized to cause pushing member 122 to be moved rightwardly into engagement with the workpieces on the transfer rail, whereupon the pushing member 122 will push the row of workpieces off the transfer rail 148 into the passageway 56 defined by the inlet guide rail structure 18. The pushing member 122 will continue its rightward movement to thus cause the workpieces to be moved into the grinding region between the wheels 13 and 14, in which region the workpieces will be sup-

ported solely by the side rails 43 and 44. When in the grinding region, the upper and lower arcuate surfaces of the workpieces will be simultaneously engaged and ground by the grinding wheels 13 and 14, respectively. The rotational directions of grinding wheels 13 and 14 are selected, in this embodiment, to cause the grinding wheels to each impose a force on the workpieces tending to move them back toward the pusher member 122, whereby the individual workpieces are thus maintained in contact with one another. For this purpose, the upper grinding wheel 13 is rotated in a clockwise direction, and the lower grinding wheel 14 is rotated in a counterclockwise direction as viewed in FIG. 2. However, this rotational arrangement may be altered.

The pushing member 122 will continue its rightward movement to cause the workpieces to be continuously and sequentially moved, one by one, through the grinding region and into the passageway 71 defined within the outlet guide rail structure 21. This advancing movement of the pushing member and of the workpieces will continue until the forward end of the pushing member 122 has passed through the grinding region and is positioned slightly past the tooth 79 formed on the holding lever 77, which position of the pushing member 122 is illustrated by dotted lines in FIG. 6. When in this position, the cylinder 109 is then energized to retract the pushing member 122, whereupon holding lever 77 pivots downwardly (counterclockwise in FIG. 6) so that tooth 79 engages the rear surface of the endmost workpiece, thereby preventing the workpieces from being drawn back into the grinding region. Further, the engagement of the holding lever 77 with the endmost workpiece is further assisted by the stream of water which is being discharged into the grinding region from the flow passage 72, which stream of water passes between the upper surface of the tooth 79 and the periphery of the wheel 13, whereby the water imposes sufficient pressure on the tooth 79 to continuously urge it downwardly into holding engagement with the endmost workpiece. Thus, the suction created by the streams of water directed into the grinding region cannot cause the previously ground workpieces to be sucked back into the grinding region.

When the workpieces have been initially transferred from the transfer rail 148 into the inlet guide rail structure 18, then the fluid pressure cylinder 129 is energized to cause the support post 124 and turntable 123 to be moved downwardly. However, due to the coaction between the cam groove 137 and cam roller 136, the downward movement of the turntable is also accompanied by a corresponding rotational movement of the turntable so that when the turntable reaches its lowermost position, then the transfer rail 148 is positioned in substantial alignment with the loading rail 157. The operator of a machine, either during or after the lowering of the turntable, can manually position a plurality of workpieces on the loading rail 157 so that the workpieces are positioned in end-to-end relationship within a longitudinally extending row. With the transfer rail 148 aligned with the loading rail 157, the operator then grasps the handle 163 and moves the transfer slide 162 forwardly so that it slidably moves the row of workpieces from the loading rail 157 onto the transfer rail 148. The transfer slide 162 is then manually retracted to the solid line position illustrated in FIG. 13. The turntable 123, thus having a new row of workpieces positioned thereon, is now ready to be raised into a posi-

tion of alignment with the inlet guide rail structure 18. However, the raising movement of the turntable will not be initiated until the pushing member 122 has been fully retracted after having completed its previous grinding cycle. When the pushing member 122 is fully retracted, then cylinder 129 is again energized to cause an upward movement of the turntable 123 and, due to the cam-and-slot arrangement, the turntable is correspondingly angularly moved to thus position it directly in alignment with the intake guide rail structure 18. The column of workpieces mounted on the transfer rail 148 are thus positioned in alignment between the pushing member 122 and the passageway 56 to thus permit the initiation of a further grinding cycle, in substantially the same manner as described above.

In order to maintain the row of workpieces in contact with one another during the grinding operation, the retarder device 22, due to its own weight, pivots about the bolts 87 so that the rightward end of same swings downwardly to bear against the upper surfaces of the workpiece as they slidably move thereunder. This causes a frictional drag force to be imposed on the workpieces in opposition to the driving force of the pushing member 122, whereby the workpieces remain directly adjacent one another as they are continuously fed through the machine.

When the workpieces are being fed through the grinding region, a suitable cooling fluid, such as water, is supplied through all of the passages 59, 63, 72 and 74, whereby individual streams of cooling liquid are thus directed onto the peripheries of the wheels 13 and 14 adjacent the opposite sides of the grinding region. However, due to the large quantities of water supplied through these passages, and due to the pressure of the streams of water, it is necessary to substantially totally enclose and confine the grinding wheels to prevent the water from being thrown or jetted externally of the machine. For this purpose, the passageways 56 and 71 formed in the inlet and outlet guide rail structures 18 and 21, respectively, have a cross-sectional configuration substantially the same as but only slightly larger than the workpieces W. The workpieces W thus substantially totally close the passageways 56 and 71 and prevent the cooling liquid from being discharged therethrough.

The operational sequence of the machine, particularly as it relates to the electrical control circuit of FIG. 16, is briefly outlined below:

1. Press the "Master Start" button to energize the relays CRM, TR and MI, thus starting the hydraulic pump system, the lubrication

2. Press the "Reset Emerg. Stop" button to energize the emergency stop relay CRE.

NOTE: You must have the 2CR relay energized (coolant flow to the spindles or ram not advanced past the feed limit) to reset emergency.

3. Autocycle:

A. Press "Auto" button to energize relay ERA and pilot light.

B. Start upper and then lower spindles (M2-M3). Lube must be satisfactory as indicated by energization of relay 1CR.

C. Press "Start Cycle" button to energize relay 3CR. Relay 3CR energizes relay 4CR advancing ram. Elevator must be up and in line with LS-4 and LS-4 engaged.

- D. Ram engages "Start Elev. Down" limit switch LS-7, energizing relay 8CR and starting elevator down. NOTE: Elevator must engage elevator down limit switch (LS-5) before ram engages LS-8 or you will de-energize relay 4CR, thereby stopping ram.
- E. Engage feed limit switch LS-2 to energize relay 5CR, thereby starting grind feed stroke.
- F. Elevator down switch LS-5, when engaged, energizes "Load Parts" light. Operator loads parts onto elevator which causes disengagement and re-engagement with LS-9, which energizes relay 10CR.
- G. At end of grinding cycle LS-3 is engaged causing 4CR to de-energize and full depth relay 6CR to energize.
- H. Relay 6CR energizes relay 7CR returning ram.
- I. Ram when returned engages LS-1 causing de-energizing of relay 7CR and energizing of relay 9CR to cause elevator to be moved up.
- J. Elevator up and in line engages LS-4 and LS-6, re-setting load memory relay 10CR and full depth relay 6CR.
- K. Machine now ready for next cycle. Repeat steps "D" through "J."
4. Manual cycle: You must have relay 2CR energized for proper coolant flow.
- A. Press "Hand" button energize to energize relay CRH and pilot light.
- B. Press the corresponding button for the operation desired.
5. Lube mist system must be operating to start spindles, but will stop them upon a fault only if you are not advancing the ram.

ALTERNATE STRUCTURE

FIGS. 17-20 illustrate an alternate grinding machine 190 having a base 191, a pair of pedestals 192 and 193, and a column 194 mounted upon the base 191 to support a pair of grinding wheels 196 and 197 in a manner substantially the same as described above with respect to the grinding wheels 13 and 14, respectively.

The grinding machine 190 has a pair of guide rails 198 and 199 which are rigidly secured to and extend between the pedestals 192 and 193. As shown in FIGS. 19 and 20, the rails 198 and 199 are vertically elongated and have opposing grooves 202 and 203, respectively, in their upper, inner edges which extend the full length thereof. As shown in FIG. 20, the rails 198 and 199 are spaced from each other a distance slightly greater than the thickness of the lower grinding wheel 197. Thus, the grinding wheel 197 can extend upwardly between the rails 198 and 199 to engage the inner concave surface of a substantially semi-cylindrical workpiece W' when the lower edges thereof are being guided along and within the grooves 202 and 203.

The upper grinding wheel 196 and lower grinding wheel 197 cooperate to simultaneously engage the upper and lower surfaces, respectively, of the workpiece W' substantially as set forth above with respect to the grinding wheels 13 and 14. In this embodiment, however, the grinding wheels 196 and 197 are intentionally rotated in the same clockwise direction as appearing in FIG. 18 to cancel out their individual tendencies to move the workpieces in one direction.

An intermediate rail support 204, mounted upon the base 191 between the pedestals 192 and 193, minimizes lateral deflection of the rails 198 and 199 during

the operation of the alternate grinding machine 190. Suitable nozzles 206 and 207 (FIG. 18) may be connected to a source of coolant-lubricant fluid, not shown, and directed at the grinding wheels 196 and 197 for conventional purposes. The excess fluid can, in a substantially conventional manner, be collected in a pan 208 after which it can be filtered and returned to the supply, also in a conventional manner.

The workpieces W' are moved along the rails 198 and 199 by a pair of resiliently flexible drive wheels 211 and 212. The drive wheel 211, like the grinding wheel 196, has a concave peripheral surface which fits around the outer curved surface of the workpiece 20. The lower drive wheel 212 has a convex peripheral surface which is received into the concave lower surface of each workpiece W'. The upper wheel 211 is mounted upon a shaft 213 rotatably supported by a bearing assembly 214 which is supported upon the column 194 by means of a mounting plate 216.

The lower drive wheel 212 is mounted upon a shaft 217 which is rotatably supported by the bearing assembly 218, which in turn is mounted upon the column 194 by the mounting plate 219. The gear box 222 (FIG. 19) is supported upon the column 194 between the mounting plates 216 and 219, and the output shaft 223 thereof is connected to the shaft 213 by means of the V-belt drive 224.

The shaft 217 is connected to an idler shaft 226 by gears 227 and 228, and said idler shaft 226 is also rotatably supported by the bearing assembly 218. The idler shaft 226 is connected to the output shaft 223 by means of a V-belt drive 229.

The gear box 222 is in turn driven by a motor 232, which is mounted upon the column 194. A relatively slow and adjustable rotational speed of the drive wheels 211 and 212 can be produced by the gear box 222.

By means of the foregoing drive mechanism, the drive wheels 211 and 212 are rotated in opposite rotational directions so that their adjacent peripheral surfaces are moving in substantially the same direction as they engage opposite sides of the workpiece passing therebetween. Accordingly, the drive wheels 211 and 212 provide a positive continuous urging of the workpieces W' along the rails 198 and 199 in a rightward direction, as appearing in FIG. 18.

A hydraulic actuator 233 may be mounted upon the pedestal 192 so that its piston rod 234 extends rightwardly from the pedestal for engagement with the workpieces W' whereby said workpieces are moved along the rail into positions between the wheels 211 and 212. This arrangement permits automatic feeding of the machine since the piston 234 can be actuated to permit the loading of workpieces W' onto the rails, either individually or in groups, while the drive wheels 211 and 212 continue to urge the workpieces along the rails.

A pair of drag wheels 237 and 238, which may be substantially identical with the drive wheels 211 and 212, respectively, are secured upon shafts 239 and 240, which are supported by a bracket 241 upon the pedestal 193. The shafts 239 and 240 are each engaged by adjustable and frictional brake means, such as that indicated at 242 in FIG. 17, for resisting rotation of the shafts, hence, the drag wheels.

An endless conveyor belt 236 may be mounted near and beneath the rightward ends of the rails 198 and 199 so that finished workpieces W' can be discharged onto

said conveyor belt and automatically carried away from the machine.

In operation, workpieces W' are placed either individually or in groups, upon the rails 198 and 199 (FIG. 17) between the piston 234 and the drive wheels 211 and 212. The pressure applied by the pressure cylinder 233 moves the workpieces W' along the rails and into engagement by the wheels 211 and 212, which furnish the primary driving force for moving the workpieces into position between the grinding wheels 196 and 197. After the desired grinding operation has been performed by the wheels 196 and 197, the workpieces are then moved by their interengagement along the rightward ends of the rails 198 and 199 until they drop therefrom onto the conveyor belt 236 which carries them away from the machine.

However, the rightward movement of the workpieces W', after they pass the grinding wheels, is opposed by the drag wheels 237 and 238. Thus, the group of workpieces between the drive wheels 211, 212 and the drag wheels 237, 238 are positively held in an aligned, side-by-side group which facilitates the grinding and conveying operations.

Although a particular preferred embodiment of the invention has been disclosed in detail for illustrative purposes, it will be recognized that variations or modifications of the disclosed apparatus, including the rearrangement of parts, lie within the scope of the present invention.

The embodiments of the invention in which an exclusive property or privilege is claimed are defined as follows:

1. A machine for successively grinding a plurality of workpieces, comprising:
  - base means;
  - a pair of bearing assemblies supported upon said base means, at least one of said assemblies being adjustable toward and away from the other;
  - a pair of parallel spindles, one thereof being rotatably supported in, and extending from, each of said bearing assemblies;
  - driving means supported by said base means and connected to said spindles for rotating same;
  - a pair of radially aligned grinding wheels mounted upon the extended ends of said spindles, said grinding wheels having their peripheries near to but spaced from one another to define a grinding region therebetween;
  - elongated, substantially horizontal guide structure associated with said grinding region for guiding a group of workpieces toward, through, and away from said grinding region, said guide structure extending substantially tangentially between said wheels;
  - said guide structure including tunnel-like inlet and outlet guide means extending away from said region, the adjacent ends of said inlet and outlet guide means being positioned closely adjacent the peripheries of said grinding wheels, said inlet and outlet guide means having passageways extending therethrough and communicating directly with said grinding region, said passageways having cross-sections substantially the same as, but slightly larger than, the cross-section of the workpieces; and
  - drive means, including a reciprocating pushing member, for engaging a row of workpieces for slidably

moving the workpieces through the passageway of the inlet guide means, through the grinding region and into the passageway of the outlet guide means.

2. A grinding machine according to claim 1, wherein each of said inlet and outlet guide means includes a fluid passage therethrough and terminating directly adjacent said grinding region for permitting streams of cooling fluid to be discharged directly into said grinding region from opposite sides thereof.

3. A grinding machine according to claim 1 for simultaneously grinding opposite concave and convex surfaces of a workpiece, wherein one of said grinding wheels has a convex periphery and the other grinding wheel has a concave periphery, whereby said peripheries define a grinding region therebetween substantially corresponding to the cross-section of said workpieces;

said elongated guide structure including a pair of elongated parallel and spaced guide rails extending horizontally along the opposite axial sides of said other grinding wheel, said pair of guide rails comprising a portion of said inlet and outlet guide means and also extending through said grinding region for slidably supporting the workpieces as they move therethrough; and

said inlet and outlet guide means each including a center rail disposed between said side guide rails and terminating directly adjacent said grinding region, each center rail having an upper surface adapted to slidably support one of the external surfaces of said workpiece.

4. A grinding machine according to claim 3, wherein the upper surface of each center rail has a convex configuration, and each of said inlet and outlet guide means also having a top wall having a lower concave surface spaced above the upper convex surface of its respective center rail for defining said passageway therebetween.

5. A grinding machine according to claim 4, wherein the top wall of each guide means has a fluid passage extending therethrough and communicating with said grinding region directly adjacent the periphery of the uppermost grinding wheel for permitting streams of cooling fluid to be directed into said grinding region from opposite sides of a plane defined by the axes of said spindles, and each of said center rails also having a fluid passage therein communicating with said grinding region directly adjacent the periphery of the lowermost grinding wheel for also directing a pair of streams of cooling fluid into said grinding region from the opposite sides of said plane, and said workpieces when disposed within said guide passageways substantially totally closing same for preventing the cooling fluid from being discharged through the passageways formed in said inlet and outlet guide means.

6. A grinding machine according to claim 3, further including a retarder device disposed adjacent the other end of said outlet guide means for engaging said workpieces and imposing a retarding force thereon in opposition to the pushing force imposed on said workpieces by said pushing member.

7. A grinding machine according to claim 3, further including loading means for permitting one group of workpieces to be disposed in an end-to-end relationship within a longitudinally extending row while said pushing member is simultaneously pushing another group of workpieces through the grinding region; and

transfer means coacting with said loading means for permitting said one group of workpieces to be moved into a position substantially in alignment with the passageway of said inlet guide means after completion of a previous grinding cycle and retraction of the pushing member.

8. A grinding machine according to claim 7, wherein said loading means includes an elongated substantially horizontally extending rail structure adapted to have said one group of workpieces positioned thereon, and means mounting said rail structure for substantially horizontal swinging movement between a first position wherein the rail is inclined at an angle relative to the longitudinal direction of the passageway of said inlet guide means and a second position wherein said rail is substantially aligned with said passageway.

9. A grinding machine according to claim 7, wherein said loading means includes an elongated rail structure adapted to have said one group of workpieces loaded thereon, and means mounting said rail structure for movement between a loading position wherein said rail structure is substantially vertically spaced from the passageway of said inlet guide means and a unloading position wherein said rail structure is substantially aligned with the passageway of said inlet guide means.

10. A grinding machine according to claim 7, wherein said loading means includes elongated stationary loading rail means, and means mounting same in a stationary position, said loading rail means having a configuration permitting said one group of workpieces to be loaded thereon;

said loading rail means being angularly inclined relative to the longitudinal direction of said guide structure and being disposed at an elevation substantially below said guide structure;

said transfer means including elevator means mounted for movement between a lowered loading position and a raised unloading position, said elevator means having elongated transfer rail means mounted thereon adapted to slidably receive thereon said one group of workpieces, and means for causing horizontal angular movement of said transfer rail means between first and second rotational positions, said transfer rail means being disposed directly adjacent and in alignment with said loading rail means when said elevator is in said lowered loading position and said transfer rail means is in said first rotational position, said transfer rail means being in alignment with and substantially adjacent said inlet guide means when said elevator means is in said raised unloading position and said transfer rail means is in said second rotational position; and

said loading means including reciprocal slide means for engaging said one group of workpieces mounted on said loading rail means for slidably moving same onto said transfer rail means when said transfer rail means is in said first rotational position and said elevator means is in said lowered loading position.

11. A grinding machine according to claim 10, wherein said pushing member, when in its fully retracted position, is spaced from said one end of said inlet guide means by a distance sufficient to permit said transfer rail means to be disposed therebetween when said elevator is in said raised unloading position, whereby extension of said pushing member causes

5

same to engage said one group of workpieces on said transfer rail means and slidably push same into the passageway of said inlet guide means.

12. A machine for successively grinding a plurality of workpieces, comprising:

base means;

a pair of bearing assemblies supported upon said base means;

a pair of spindle assemblies, one thereof being rotatably supported in, and extending from, each of said bearing assemblies;

first drive means supported by said base means and connected to said spindles for rotating same;

a pair of radially aligned grinding wheels mounted upon said spindles, said grinding wheels having their peripheries near to but spaced from one another to define a grinding region therebetween; elongated guide structure associated with said grinding region for guiding a group of workpieces towards, through and away from said grinding region, said guide structure including tunnel-like inlet and outlet guide means extending toward and away from said grinding region, respectively, the adjacent ends of said inlet and outlet guide means being positioned closely adjacent the periphery of said grinding wheels, said inlet and outlet guide means having passageways extending therethrough and communicating directly with said grinding region, said passageways having configurations for accommodating but closely confining the workpieces as they are slidably moved therethrough; and

second drive means for engaging the workpieces for slidably moving the workpieces through the passageway of the inlet guide means, through the grinding region and into the passageway of the outlet guide means.

13. A grinding machine according to claim 1, further including a retarder device disposed adjacent the other end of said outlet guide means for engaging said workpieces and imposing a retarding force thereon in opposition to the pushing force imposed on said workpieces by said pushing member.

14. A grinding machine according to claim 1, further including loading means for permitting one group of workpieces to be disposed in an end-to-end relationship within a longitudinally extending row while said pushing member is simultaneously pushing another group of workpieces through the grinding region; and transfer means coacting with said loading means for permitting said one group of workpieces to be moved into a position substantially in alignment with the passageway of said inlet guide means after completion of a previous grinding cycle and retraction of the pushing member.

15. A grinding machine according to claim 14, wherein said loading means includes an elongated substantially horizontally extending rail structure adapted to have said one group of workpieces positioned thereon, and means mounting said rail structure for substantially horizontal swinging movement between a first position wherein the rail is inclined at an angle relative to the longitudinal direction of the passageway of said inlet guide means and a second position wherein said rail is substantially aligned with said passageway.

16. A grinding machine according to claim 14, wherein said loading means includes an elongated rail structure adapted to have said one group of workpieces loaded thereon, and means mounting said rail structure for movement between a loading position wherein said rail structure is substantially vertically spaced from the passageway of said inlet guide means and a unloading position wherein said rail structure is substantially aligned with the passageway of said inlet guide means.
